UNITED STATES PATENT OFFICE.

JOSEPH GLASSBERG, OF NEW YORK, N. Y.

DESIGN FOR A BRACKET.

55,603.

Specification for Design.

Patented July 6, 1920.

Application filed January 16, 1920. Serial No. 351,954. Term of patent 14 years.

To all whom it may concern:

Be it known that I, JOSEPH GLASSBERG, a citizen of the United States, residing at 1457 Broadway, in the city of New York and State of New York, have invented a new, original, and ornamental Design for a Bracket, of which the following is a specification, reference being had to the accompanying drawing, forming a part thereof.

The drawing shows a front perspective view of the bracket illustrating my new design.

I claim:

The ornamental design for a bracket substantially as shown.

JOSEPH GLASSBERG.
